UNITED STATES PATENT OFFICE

157,992

VESSEL

Ernst A. Meyer, Cincinnati, Ohio, and August M. Deering, Chicago, Ill.; said Deering assignor to said Meyer

Application November 13, 1947, Serial No. 142,510

Term of patent 14 years

(Cl. D71—1)

To all whom it may concern:

Be it known that we, Ernst A. Meyer and August M. Deering, both citizens of the United States and residing at Hamilton County, at Cincinnati, Ohio, and Cook County, at Chicago, Illinois, respectively, have invented a new, original, and ornamental Design for a Vessel, of which the following is a specification, reference being had to the accompanying drawing, forming a part thereof.

Figure 1 is a general side elevational view, illustrating a vessel constructed according to our new design.

Figure 2 is a top plan view.

Figure 3 is a view illustrating the forward end or bow of the vessel.

Figure 4 is a view similar to Figure 3 illustrating the rearward or stern of the vessel.

The characteristic features of our design reside in the portion shown in the full lines of the drawing.

We claim:

The ornamental design for a vessel, substantially as shown and described.

ERNST A. MEYER.
AUGUST M. DEERING.
